CLAIM

The ornamental design for a network attached storage, as shown and described.

DESCRIPTION

FIG. 1 is a front, left side and top perspective view of a network attached storage showing our new design;
FIG. 2 is a rear, right side and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view taken from detail circle 9 in FIG. 1.

The dash-dot broken lines in the drawings depict the portions of the network attached storage that form no part of the claimed design.

(Continued)

The dot-dash broken lines in the drawings depict the boundaries of the enlarged views and form no part of the claimed design.

1 Claim, 9 Drawing Sheets
